ATTORNEY

UNITED STATES PATENT OFFICE.

WALTER A. INMAN, OF WAUKEGAN, ILLINOIS.

CARBURETOR.

Application filed August 26, 1920. Serial No. 406,175.

To all whom it may concern:

Be it known that I, WALTER A. INMAN, a citizen of the United States, and resident of Waukegan, in the county of Lake and State 5 of Illinois, have invented new and useful Improvements in Carburetors, of which the following is a description, reference being had to the accompanying drawings, which are a part of this specification.

10 The invention relates to carburetors more particularly for use in forming a combustible mixture for internal combustion engines.

One of the objects of this invention is to 15 provide an apparatus for thoroughly mixing liquid fuel by mechanical agitation and churning to such to such an extent that some of the fuel is vaporized even though the fuel is not readily volatile under ordinary conditions.

A further object of the invention is to provide means for returning any unmixed fuel back into the mixing apparatus.

The invention further consists in the several 25 features hereinafter set forth and more particularly defined by claims at the conclusion hereof.

In the drawings: Fig. 1 is a vertical section view of a device embodying the invention, Fig. 2 is a section taken on the line 30 2—2 of Fig. 1.

In the drawings the numeral 3 designates a float chamber provided with a float 4 carrying a valve 5 controlling the supply of 35 fuel from a supply pipe 6. A spring pressed plunger 7 mounted in the chamber 3 may be pressed down against the float 4 for the purpose of priming the chamber, the depression of the float causing the opening of the 40 valve 5.

A fuel conduit 8 leads from the float chamber to a well 9 in a chamber 10. The passage of fuel from the conduit 8 to the well 9 is controlled by an adjustable needle valve 45 11.

The chamber 10 is provided with an air inlet 12 and a pipe 13 leads from the inlet end of the chamber 10 to the float chamber 3 to equalize the pressures in these chambers.

50 A partition 14 extends across the chamber 10 in front of the air inlet and down to a position close to the surface of the fuel in the well 9, so that the air entering the inlet 12 in passing over the fuel in the well 9 is forced to pass through a constricted open-

ing and by an increased suction effect carry some of the fuel along with it into the main portion of the chamber.

The inner end of the chamber 10 terminates in a centrally disposed inlet to an impeller casing 15 which has a tangentially disposed outlet 16 for connection with the intake manifold of the engine.

An impeller 17 has its shaft 18 journalled in the casing 15 and suitably connected to 65 an electric motor 19, preferably one having series characteristics and of low voltage so that it may be run from the starting or ignition battery of a motor driven vehicle. The impeller with the casing forms a turbo 70 compressor and also a mixing device.

A butterfly or other suitable throttle valve 20 in the outlet 16 controls the supply of mixture to the intake manifold and also controls the operation of the compressor.

To prevent the collection of any liquid fuel in the impeller casing, a pipe 21 leads from the bottom thereof back into the chamber 10 above its bottom and adjacent the inlet of impeller casing so that liquid fuel in 80 the impeller casing draining down into this pipe may be taken up by the air and again subjected to the mixing action of the impeller. This pipe is flattened or otherwise suitably shaped at the bend 21' to spread out 85 the fuel that may drain into it from the impeller casing, in a thin layer so as to facilitate its being again taken up by the air and returned to the impeller casing.

In case kerosene or other not readily volatile fuel is used, gasoline may be introduced into the chamber 10 on starting the engine through a priming valve 22 connected by a pipe 23 with a source of fuel supply.

When the engine is started and the motor 95 19 put in operation the suction created by the rapidly rotating impeller 17 draws a stream of air over the liquid fuel in the well 9 and through the opening 24 formed between the dam 14 and the surface of the 100 fuel and the air picks up some of the fuel from the well and carries it into the chamber 10 and thence to the casing 15 where it is thoroughly mixed with the air by the vanes of the impeller and the mixture thus formed is delivered under a slight pressure to the outlet 16, from whence it passes through the manifold to the cylinder or cylinders of the engine. In this way a thorough and efficient mixing of the air and fuel

is obtained and a greater charge weight furnished to the engine than is possible with the usual form of carburetor.

In cool weather the motor 19 is placed in 5 operation preferably just before the engine is turned over for starting in order that the impeller may be rotated rapidly to effect an initial turbulence, which will mix any condensed fuel that may be present. As the pis- 10 tons are caused to move downwardly on their suction strokes during the starting operation the impeller will immediately draw fuel and air from the chamber 10 and under the normal slight pressure will deliver a properly 15 mixed charge to the cylinders where it will be readily ignited to start the engine promptly.

The throttle valve 20 serves to control the quantity of mixture delivered to the intake 20 manifold and also controls the operation of the impeller as a partially closed throttle will produce a back pressure in the impeller casing which will cause a decrease in speed 25 of the motor 19 as the load on the motor is increased under such a condition and an open throttle will cause an increase in speed of the motor.

I desire it to be understood that this invention is not to be limited to any specific 30 form or arrangement of parts except in so far as such limitations are specified in the claims.

What I claim as new and desire to secure by Letters Patent is:

35 1. In a carburetor, the combination of a fan casing, a power-driven centrifugal fan in said casing, the casing having a central

inlet passage conducting air and fuel to the central portion of the fan, a tangential discharge passage, and a conduit leading from 40 the fan casing and extending into the inlet passage with its opening directed toward the central portion of the fan for returning any unmixed fuel to said inlet passage.

2. In a carburetor, the combination of a 45 fan casing, a power-driven centrifugal fan in said casing, the casing having a central inlet passage conducting air and fuel to the fan and a tangential discharge passage, and a by-pass conduit connecting the outer portion of the fan casing with the inlet passage, whereby unmixed fuel will be returned from 50 the fan casing to the inlet passage by an air current from the fan.

3. In a carburetor, the combination of a 55 fan casing, a power-driven centrifugal fan in said casing, the casing having a central inlet passage conducting air and fuel to the central portion of the fan and tangential discharge passage, and a U-shaped conduit 60 leading from the fan casing and extending into the inlet passage with its opening directed toward the central part of the fan for returning any unmixed fuel to said passage, the transverse portion of said conduit 65 being flattened to spread out the fuel at this part of the conduit.

In testimony whereof, I affix my signature, in presence of two witnesses.

WALTER A. INMAN.
